US0D1063714S

(12) **United States Design Patent** (10) **Patent No.:** **US D1,063,714 S**
(45) **Date of Patent:** **** Feb. 25, 2025**

(54) **FRAME**

(71) Applicant: **ZHEJIANG AIJIU TECHNOLOGY CO., LTD**, Lishui (CN)

(72) Inventor: **Xin Ying**, Lishui (CN)

(73) Assignee: **ZHEJIANG AIJIU TECHNOLOGY CO., LTD**, Lishui (CN)

(**) Term: **15 Years**

(21) Appl. No.: **29/978,458**

(22) Filed: **Dec. 12, 2024**

(51) **LOC (15) Cl.** **12-11**

(52) **U.S. Cl.**

USPC **D12/111**

(58) **Field of Classification Search**

USPC D12/110, 111, 117-119, 122-127, 159; D21/424-435, 664

CPC B62K 25/02; B62K 25/06; B62K 21/02; B62K 19/16; B62K 25/08

See application file for complete search history.
